Attorney

UNITED STATES PATENT OFFICE.

JAMES J. CONNELL, OF DETROIT, MICHIGAN.

REAMER.

Application filed September 4, 1920. Serial No. 408,300.

To all whom it may concern:

Be it known that I, JAMES J. CONNELL, citizen of the United States, residing at Detroit, county of Wayne, State of Michigan, have invented a certain new and useful Improvement in Reamers, and declare the following to be a full, clear, and exact description of the same, such as will enable others skilled in the art to which it pertains 10 to make and use the same, reference being had to the accompanying drawings, which form a part of this specification.

My invention relates to reamers shown in the accompanying drawings and more particularly described in the following specification and claims.

One of the objects of my invention is to construct a reaming tool having radial blades, of relatively few parts, adapted for 20 a minute longitudinal and radial adjustment, whereby they may be expanded to adapt the tool for the work and to compensate for wear, and the grinding of the blades when sharpened.

25 A further object of the invention consists in the means for quickly and rigidly securing the blades when adjusted, so that no looseness of action or chattering of the blades will occur while at work.

30 With the foregoing and other objects in view which will appear as the description proceeds the invention further resides in the combination and arrangement of parts and in the details of construction hereinafter described and claimed, it being understood that changes may be made in the precise embodiment of the invention herein disclosed without departing from the spirit of the same.

In the accompanying drawings:—

40 Figure 1 is a longitudinal sectional view of the reaming tool.

Figure 2 is an elevation with parts in section.

45 Figure 3 is an elevation showing a modification in which the blades are disposed in inclined longitudinally arranged grooves.

Figure 4 is a fragmentary cross sectional view showing the manner in which the inclined or cutter blades shown in Figure 3 50 are held in position by the set screws.

Figure 5, is an elevation of one of the cutter blades.

Referring now to the letters of reference placed upon the drawings:—

55 A, denotes the body of the tool. B, indicates a plurality of peripheral grooves in

the body of the tool, which may be disposed parallel with its longitudinal axis, or may be inclined at an angle thereto, as indicated in Figure 3;—the bottom of the grooves being 60 inclined outwardly toward the front or forward end of the body portion.

C, indicates a series of removable blades respectively lodged in the grooves B, of the body portion.

E, are set screws, screwed into the body portion A of the tool, having projecting heads E' lodged in the longitudinal grooves D, formed in the sides of the cutter blades;—the head of the set screws being chamfered 65 as indicated at e, on their underside to bear against the bevelled edge d, of the longitudinal grooves D, of the cutter blades, in order that upon the adjustment of the screws the blades may be forced snugly against the 70 side and bottom walls of the groove in which they are lodged.

When the cutter blades E are arranged parallel with the longitudinal axis of the tool,—(as shown in Figures 1 and 2) the set 75 screws E are lodged in holes tapped in the body of the tool in a line tangent to an arc concentric with its central bore, as shown in the latter view.

When the cutter blades are lodged in 80 grooves formed at an angle to its longitudinal axis, (as shown in Figure 3), the set screws enter holes tapped at an angle or radially into the body of the tool in order to provide full body stock surrounding the 85 head of the set screw, as shown in Figure 4.

To overcome the stress caused by the lateral thrust of the cutter blades against the heads of the set screws E, the tapped holes in the body are counterbored to receive the 90 heads of the screw, the surrounding wall of the body portion thus serving to support the head of the set screws against the lateral thrust of the cutter blades.

F, indicates an adjustable collar screwed 95 upon the body portion A having an inclined end wall adapted to overlap the inclined ends C' of the several cutter blades.

G, denotes a set screw carried by the adjustable collar having a projecting end G' 100 adapted to enter the longitudinal grooves D in the body portion, to secure the collar when adjusted.

Having now indicated the several parts by reference letters the construction and operation of the device will be readily understood.

When it is desired to take up wear or to adjust the cutter blades for the work to be executed the set screws E engaging the several cutter blades are first released.

5 The set screw G is then unscrewed sufficiently to release the collar F, which is then adjusted,—forcing the blades simultaneously beyond the end of the body portion and outwardly to meet the requirements of 10 the work upon which it is to operate.

Upon properly adjusting the blades by means of the collar F, the set screw G is again turned to secure the collar against accidental release, which together with the several set screws E, serves to secure the blades 15 in their respective slots.

Having thus described my invention what I claim is:—

1. In a reamer, a body portion having a 20 plurality of grooves to receive a series of cutter blades, a plurality of removable cutter blades fitted to said grooves each having an inner slanting end, a thrust collar screwed upon the body portion and having an inclined face adapted to impinge upon the slanting ends of the said cutter blades, and 25 a set screw carried by the collar and having

a reduced portion projecting into one of the several grooves of the body portion, whereby the thrust collar is securely locked in its 30 adjustment and held against accidental release.

2. In a reamer a body portion having a plurality of radial tapering grooves provided with extended portions, cutter blades 35 mounted in the grooves and having an inclined end, a thrust collar carried by the body portion and having an inclined face contacting with the inclined end of the cutter blade, a set screw having a smooth reduced portion carried by the said collar and projecting into the extended portion of the groove, the said reduced portion having a flat lower face contacting with the inclined base of the groove at its edge and 40 adapted to bite into the said inclined face whereby chattering is eliminated.

In testimony whereof, I sign this specification in the presence of two witnesses.

JAMES J. CONNELL.

Witnesses:

S. E. THOMAS,
IDA GOREN.
